COOLING DEVICE FOR INTERNAL-COMBUSTION ENGINES.

1,422,565.

Specification of Letters Patent. Patented July 11, 1922.

Application filed November 9, 1921. Serial No. 514,045.

To all whom it may concern:

Be it known that I, CARL GRUNWALD, residing at Essen-Bredeney, Germany, a citizen of the German Republic, have invented 5 a certain new and useful Improvement in Cooling Devices for Internal-Combustion Engines, of which the following is a specification.

This invention relates to cooling devices 10 for internal combustion engines and in particular to those cooling devices in which, in order to protect the portions of the walls of the combustion chamber which are most jeopardized by unadmissibly great fluctuations in temperature, exchangeable water-cooled chambers are placed in front of these wall portions, in particular at the points where the inlet openings for the valve cages are situated, said valve cages passing freely 15 through said cooling chambers so that the latter are not hindered by the valve cages to freely expand.

Now the object of the present invention is to hold these water-cooled chambers 20 themselves free from strains as far as possible.

This object is attained by so constructing these freely movable and expansible chambers that the walls, remote from the 25 combustion chamber, of these cooling chambers can likewise be struck by the hot combustion gases.

An embodiment of the subject-matter of the invention is illustrated in the accompanying drawing by way of example, the drawing showing, in vertical section, the 30 questioned portion of the working cylinder of a vertical internal combustion engine having the valves arranged in the 40 wall of the cylinder.

A denotes the double-walled working cylinder, B the cylinder cover, C the working piston and D a scavenging valve arranged in the cylinder wall.

45 The apertures through which the several valves pass—only one valve D being shown in the drawing—are surrounded by cooling chambers which can be easily exchanged. As shown in the drawing, these chambers 50 are, for the sake of simplicity, united into one closed cooling ring E which is fitted with a hollow, water-cooled bottom protecting the cylinder cover and stiffened by ribs. The wall portions, facing the combustion 55 chamber, of the cooling chamber E are

made very thin in order to facilitate, as far as possible, the carrying away of the heat and to obviate great differences in temperature and strains in these wall portions.

The scavenging valve D passing through 60 the cylinder wall penetrates the cooling chamber E but, in order to avoid strains in said chamber and to not injure the free movability of the latter, the packing of the valve D is not placed at this chamber but 65 at the cylinder wall. The supply to the chamber E and the outlet therefrom, of the cooling water takes place preferably through freely movable pipes F, F¹ which are packed by stuffing boxes or piston rings 70 on the cylinder cover B and do not, therefore, injure the freedom of movability of the cooling chamber E.

In order to prevent that the wall portions of the cooling chamber, facing the combustion chamber and the cover or the cylinder wall may be heated up to different height when the engine is running, and strains will consequently arise in the chamber wall, care is taken according to the present invention 80 that the portions of the chamber E remote from the combustion chamber, are sufficiently heated likewise.

To this end the wall, of the cooling chamber, adjacent to the cylinder wall, and the 85 cylinder cover is so formed at the greater part of its bearing surface that hollow spaces e¹ are produced in which the hot combustion gases enter, the different heating of the wall portions of the cooling chamber thus being 90 compensated for. The entrance of the hot gases in the hollow spaces e¹ is enabled by the cooling chamber having a sufficiently large clearance on all sides, particularly on its periphery, a condition required also with 95 regard to the necessary freedom of movability and expansion of the chamber E.

In order to facilitate the entrance of the combustion gases in the hollow spaces e¹ these spaces are preferably connected to each 100 other and to the combustion chamber by means of grooves provided in the outer walls of the chamber E, see the grooves e² shown in the drawing.

Claims.

1. A cooling device for internal combustion engines having a cylinder cover over its combustion chamber, said device comprising an independent hollow member at the combustion end of the cylinder, said member 110

having apertures for receiving the valve cages and spaces for cooling fluid, surrounding said valve apertures, means for exposing the walls of said hollow member, remote 5 from said combustion chamber, to the combustion gases of the engine.

2. A cooling device for internal combustion engines having a cylinder cover over its combustion chamber, said device comprising an exchangeable hollow member at 10 the combustion end of the cylinder, said member having apertures for receiving the valve cages and spaces for cooling fluid, surrounding said valve apertures, recesses 15 between the outer surface of the walls, of said hollow member, remote from said combustion chamber, and the adjacent parts of the cylinder and the cylinder cover, and connecting means between said recesses and 20 between said combustion chamber and said recesses.

3. A cooling device for internal combustion engines having a cylinder cover over its combustion chamber, said device comprising 25 a removable hollow member at the combustion end of the cylinder, said member having

apertures for receiving the valve cages and spaces for cooling fluid, surrounding said valve apertures, recesses in the outer surface of the walls, of said hollow member, remote 30 from said combustion chamber, and connecting means between said recesses and between said combustion chamber and said recesses.

4. A cooling device for internal combustion engines having a cylinder cover over 35 its combustion chamber, said device comprising an exchangeable hollow member at the combustion end of the cylinder, said member having apertures for receiving the valve cages and spaces for cooling fluid, surrounding said valve apertures, recesses in 40 the outer surface of the walls, of said hollow member, remote from said combustion chamber and grooves in the wall portions adjacent said recesses, said grooves connecting said recesses with each other and with the combustion chamber. 45

The foregoing specification signed at Essen, Germany, this eighteenth day of October, 1921.

CARL GRUNWALD.
